UNITED STATES PATENT OFFICE.

EDITH L. LOPEZ, OF NEW YORK, N. Y.

DOLL.

1,353,406.

Specification of Letters Patent. Patented Sept. 21, 1920.

Application filed April 2, 1920. Serial No. 370,640.

To all whom it may concern:

Be it known that I, EDITH L. LOPEZ, a citizen of the United States, residing at New York, in the county of New York, State of New York, have invented certain new and useful Improvements in Dolls; and I do hereby declare the following to be a full, clear, and exact description of the invention, such as will enable others skilled in the art to which it appertains to make and use the same.

My invention relates to dolls, and its object is to produce an inexpensive little doll which can be simply and easily made, is unbreakable and durable, and will present a quaint and peculiarly attractive appearance. I have discovered that such a little doll can be made by the simple expedient of building the body thereof upon a spool, or spool-shaped base. The results produced are very interesting, and depend for their effectiveness upon certain features of the spool form which I adapt to the end of doll-making in a novel manner, which shall be clearly set forth in the description which follows.

When placed upon end the lower flange of the spool forms a substantial pedestal for the little doll, and serves as an excellent substitute for feet, while the shank successfully forms the office of legs and lower body portion in an effective manner. One of the most noteworthy features of my invention, however, resides in making the upper flange of the spool coincide with the bust line of the figure, thus producing a fullness at this point having a strikingly natural effect. The bust, which is of stuffed cloth, is drawn over the upper flange and bound to the spool base by means of a string or thread wound tightly around the shank thereof immediately below the flange. In order to imitate the human figure a little more closely, that part of the upper flange which would be on the back of the doll is whittled away to give a straight line effect. The figure thus made may be dressed as fancy may dictate.

The particular advantages which I obtain are two: first, a natural fullness at the bust line of the little doll is easily obtained, and second, the head, arms and shoulders are at the same time so securely fastened to the base that not even rough handling by a child is likely to dislodge them.

My invention will be more easily under-

stood by referring to the accompanying drawings, in which:

Figure 1 is a sketch of a finished and dressed doll made in accordance with my invention showing the spool in dotted lines; and

Fig. 2 is a side elevation of an undressed doll part being drawn in section. A dress skirt is also shown fastened to the spool by the same means employed in securing the bust thereto.

The spool which I employ may be of almost any type depending upon the size of the doll to be made. A small doll may be built around a small spool commonly used to carry thread for domestic purposes, although the spool which I have shown on the drawings is of the larger type around which ribbons are usually wound. Spools are, for the most part, a waste product thrown away after use. My invention provides a unique means for utilizing them. In the drawings, 1 represents the spool having a shank 2 and upper and lower flanges 3 and 3', respectively. The upper flange is cut away at 4 to give the effect of a flat back. The bust of the doll is made of a cloth covering 5 stuffed with rags 6, or any other suitable stuffing material. The cloth 5 is continued beyond the stuffing to form an under-skirt portion 7 which is used in fastening the head, arms and shoulders to the base. The stuffed head, arms and shoulders are placed upon the spool in the manner shown, and secured thereto by wrapping a string or thread 8 tightly about the depending under-skirt 7 and the shank of the spool immediately below the upper flange 3 or by gluing the upper portion of the underskirt to the shank of the spool immediately below the flange. The two parts of the doll are thereby securely fastened together, and at the same time the upper flange of the spool co-operates with the head and shoulders to produce an effective imitation of bust fullness.

This figure may now be dressed in any approved fashion. I have shown the use of a simple dress skirt 9 which is fastened to the spool just below the upper flange thereof either by means of the same thread 8 employed in securing the bust, as shown in Fig. 2 or by independent means, and a waist 10 which comprises a square piece of silk having a hole in the center for the head of the doll, and having two diagonally disposed

corners cut off to form the sleeves, as shown at 11. This waist is slipped over the head of the figure and the two uncut corners 12 bound around the doll's waist over the skirt 5 by means of a sash 13. A simple cap 14 may be employed if desired as well as a neck piece 15.

It is, of course, obvious that hair and features may be drawn or sewed on the head of 10 the doll in various manners which may suggest themselves, and which, of course, form no part of my invention. Neither is the specific type of dress employed of particular importance.

15 A doll produced by the method described above is unbreakable and durable, is easily made, and when finished presents an attractive and interesting appearance. Moreover, it utilizes a cheap, abundant and otherwise 20 useless article—an empty spool.

Having thus described my invention, what I claim is:

1. A doll, comprising a spool having an upper flange, and a bust provided with a 25 head, arms and shoulders, the bust being supported by the said spool flange; substantially as described.

2. A doll, comprising a spool having an upper flange, and a bust provided with a 30 head, arms and shoulders, the bust being supported by the spool flange, and having a covering material of fabric which is drawn over and secured beneath said flange; substantially as described.

35 3. A doll, comprising a spool having an upper flange, and a bust provided with a head, arms and shoulders, the bust being

supported by the said flange, and having a covering material of fabric which is drawn over and secured beneath the said flange by a 40 winding of thread or cord; substantially as described.

4. A doll, comprising a spool having an upper flange, and a bust provided with head, arms and shoulders, the bust being supported by the spool flange and having a covering material of fabric which is drawn over and secured beneath the said spool flange, the covering being continued below said spool flange to form a petticoat for the doll; 50 substantially as described.

5. A doll, comprising a spool, having a lower flange upon which the doll is adapted to stand upright and having an upper flange, a bust provided with a head, arms 55 and shoulders, the bust together with the head, arms and shoulders being supported by the said upper spool flange, and consisting of a fabric cover stuffed with a soft filling, the cover being secured to the spool 60 immediately below the upper flange thereof; substantially as described.

6. A doll, comprising a spool having an upper flange, a bust provided with a head, arms and shoulders, said bust being supported by the said flange, and said flange having a flattened rear portion to give a flat back to the doll, the covering of the bust being carried over the upper flange and secured to the spool immediately below the 70 said upper flange; substantially as described.

In testimony whereof I affix my signature.

EDITH L. LOPEZ.
